UNITED STATES PATENT OFFICE.

ISAAC N. BOOMER AND STIRLING P. LINKSWILER, OF SALIX, IOWA.

RAILROAD-TIE.

No. 818,606.

Specification of Letters Patent.

Patented April 24, 1906.

Application filed September 18, 1905. Serial No. 276,820.

To all whom it may concern:

Be it known that we, ISAAC N. BOOMER and STIRLING P. LINKSWILER, citizens of the United States, residing at Salix, in the county 5 of Woodbury and State of Iowa, have invented a new and useful Improvement in Railroad-Ties; and we do declare the following to be a full, clear, and exact description of the same, reference being had to the accompanying drawings, forming a part thereof.

Our invention relates to a combined tie and coupler, and particularly to the kind of tie made of concrete, stone, or composition, although it may be applied to ties of any material whatever.

The object of the invention is to provide ties of practical use and means for securing the ties and rails together without the use of spikes or bolts. This object is accomplished 20 by means of the device shown in the accompanying drawings, in which—

Figure 1 is a plan view of our invention. Fig. 2 is a side elevation of tie and cross-section of rails, showing also a section of coupling for binding the ties together. Fig. 3 is an inverted plan view of tie. Fig. 4 is a cross-section of tie and longitudinal section of rail viewed from the center of track. Fig. 5 is an elevation of inner end of tie and section of rail.

Like parts are designated by similar letters of reference.

A A are the rails and B B are the ties, which do not extend across the track, but 35 only for a short space on each side of the rails. The ties are each inclosed by a casing C, made of iron, steel, or other suitable metal. The upper inner edge of each casing has a tongue D, projecting toward the center of the 40 track, provided with a slot d, in which is inserted a coupler E, hooked at each end for adjustment in the slots of the tongues. The casings are open at the ends and lap under the edges of the bottom, as seen in Fig. 3, and 45 have jogs or shoulders e on the sides near the ends, making the ends smaller and the ties wedge-shaped in order that the ties may be firmly secured in the casings after being inserted through the openings in the inner 50 larger ends. Each casing is formed of two irregular parts, the division on the top being through the center, as shown by the dotted

lines in the center of the rails in Fig. 1, and on the sides and bottom just outside of the rail where the keys are adjusted. The two parts 55 are secured together at the sides by keys F, inserted in grooves G, formed from the edges of the side parts being turned out. The edges and grooves diverge toward the bottom and the keys are correspondingly larger 60 at the bottom, and being thus inversely wedge-shaped tend to draw the parts together when adjusted. The side parts of the casings which extend between the divisions on the top and the divisions on the sides and 65 bottom are free of the upper surfaces in order that when the keys are adjusted the parts may be drawn together.

The rails are secured to the casings by clamps or brackets H H, formed integral 70 with the upper surface of the casings and projecting upward therefrom on each side of the rails to conform to the shape of the sides of the rails. After the casings are adjusted to the ties and the rails had the two parts of 75 the casings are joined by the keys and firmly secured together. The whole track is thus held in position without the possibility of disturbance by the jar or movement of trains. The coupler prevents the rails from spreading 80 and there is no opposite tendency of the rails, owing to the action of the flanges of the car-wheels on the inside of the rails.

Having described our invention, what we claim as new, and desire to secure by Letters 85 Patent, is—

1. In a railroad-tie, a metal casing adapted for a short tie underneath each rail and consisting, in combination, of two parts joined on the sides of the tie, wedge-shaped keys for securing the side parts together, each of the parts having a jog on each side near the end, the ends being smaller and wedge-shaped, brackets formed integral with the casing, and projecting upward therefrom on each side of the 95 rail, and means for securing the casings together between the rails, substantially as described.

2. In a railroad-tie, the combination of a casing C formed of two parts, each of said 100 parts having jogs on the sides thereof, and being largest in the middle, the edges of the side parts which join forming grooves G, keys F, for insertion in said grooves to secure the

parts together, tongues D on the upper, inner ends of the casings, couplings E for insertion in the tongues to unite the ties, and brackets H, formed integral with the casings and conforming to the shape of the sides of the rails, substantially as described.

Witness whereof we have hereunto affi-

fixed our signatures in the presence of two witnesses.

ISAAC N. BOOMER.

STIRLING P. LINKSWILER.
